FUEL LINE FITTING RETAINER ASSEMBLY

Lawrence R. Edwards, 102N 550E,
Lafayette, Ind. 47905

Filed Oct. 4, 1971, Ser. No. 186,588

Term of patent 14 years

Int. Cl. D8—08
U.S. Cl. D8—235

Fig. - 1

Fig. - 2

Fig. - 3

Fig. - 4

Fig. - 5

FIG. 1 is a rear elevational view of a fuel line fitting retainer assembly showing my new design.

FIG. 2 is a top plan view thereof.

FIG. 3 is a front elevational view thereof.

FIG. 4 is a left-hand side elevational view thereof.

FIG. 5 is a bottom plan view thereof.

The right-hand side elevation appearance is a mirror image of the left-hand side elevation shown in FIG. 4.

I claim:

The ornamental design for a fuel line fitting retainer assembly, as shown and described.
